UNITED STATES PATENT OFFICE.

EDGAR W. CLEVELAND, OF HOLLAND, MICHIGAN.

FURNACE-RADIATOR-FLUE CLEANER.

Application filed December 19, 1921. Serial No. 523,324.

This invention relates to a furnace flue cleaner, being particularly concerned with a very simple and novel construction adapted to be inserted in the furnace radiator flue located in many makes of furnaces above the fire pot thereof and through which the heated products of combustion from the furnace pass to the smoke pipe thereof and thence outwardly to the outside. During such passage, dust, soot and ashes are deposited and the flue more or less filled in time. It is desirable that the interior of the flue or radiator be kept as clean as possible for the proper conduction of the heat to the radiator so that the same may be radiated therefrom to heat the air around the radiator which passes through the furnace pipes to the several rooms heated by the furnace. Accordingly, it is necessary that the interior of the radiator be cleaned and rid of the accumulation of soot and the like frequently, and it is to the ready accomplishment of this end that the present invention is directed. A primary object and purpose of the invention is to provide a flue cleaner for furnace radiators, simple in construction, and which can be inserted into the radiator flue at the clean-out opening therein for any desired distance within the length of the device, and so constructed that it will pass over the deposit of soot, ashes and the like as it is entered into the radiator, but will assume another position when drawn back toward the clean-out opening and scrape the deposit from the inner sides of the radiator and draw it to and out of the clean-out opening. Various other objects and purposes, relating to the practical and economical production of a device of this character capable of attaining the ends set forth will appear as understanding of the invention is had from the following description, taken in connection with the accompanying drawing, in which,

Fig. 1 is a perspective view of a simple form of furnace radiator flue cleaner, made in accordance with my invention.

Fig. 2 is an elevation of a slightly modified form of construction of the device, and

Fig. 3 is an elevation, with parts broken away and shown in section of a still further modified form of construction.

Like reference characters refer to like parts in the different figures of the drawing.

In the construction of the device, as shown in Fig. 1, a circular plate 1 of sheet metal

is used, in which two spaced apart sections 2 and 3 of the metal are pressed outwardly and formed into journals for the pivotal connection of wires or rods therewith as 60 will later appear. A handle wire 4 of any desired length at one end is formed to pass under the part 2, and have pivotal connection therewith, as indicated at 5. A distance from the connection of the wire 4 to the 65 plate 1, said wire is formed with an eye 6, and at its outer end, said wire is formed into any desired shape of handle, such as 7 for ready manual manipulation of the device. The part 2 is located relatively close to the 70 edge of the circular plate 1, as shown.

A second shorter wire or rod 8 has pivotal connection at 9 with the plate 1 at the raised section 3 thereof, which is located a short distance farther in than the raised section 2 75 and parallels the same, it being located a distance out from the center of the plate. The opposite end portion of the wire 8 passes freely through the eye 6 and is formed into a hook 10 to prevent disconnection from 80 said eye.

The wire 4 is flexible and is designed to bend as required when the plate 1 is inserted into a curved or circular radiator flue. During the insertion, it is evident that 85 the plate 1 may turn toward the wire 4, the second wire 8 sliding through eye 6 so that the plate passes over the deposit within the radiator flue. As soon as the device is pulled outward, after insertion into the radiator, the plate assumes a position, substantially at right angles to the wire 4, or like that shown in Fig. 1, being stopped in such position by the hook 10 engaging with the eye 6, whereby any deposit in front of the 95 plate is drawn outward, and the edges of the plate scrape against the inner sides of the radiator and remove the deposit therefrom. The device may be moved back and forth as many times as necessary and turned to 100 different positions for the complete scraping of the inner sides of the radiator flue and removal of the deposit from said flue out through the clean-out opening.

In Fig. 2, the construction is slightly 105 modified in that a light coiled spring 11 is placed around the wire 8 between the eye 6 and the point of connection of the wire to plate 1. This spring is compressed when the plate is moved toward the wire 4, as 110 indicated in dotted lines in Fig. 2, and aids in throwing the plate back to normal full

line position. The spring yields when the plate is inserted into the radiator flue but throws the plate back immediately when the device is moved in the opposite direction for withdrawal.

In Fig. 3, the plate 1^a instead of being flat is dished in form, making a scoop for the removal and withdrawal of the deposit, being somewhat more effective in operation though 10 slightly more difficult to manufacture. With any of the forms shown, the ready cleaning and scraping of radiator flues in furnaces may be easily accomplished, with the assurance that on outward movement of 15 the device, the plate 1 or 1^a automatically assumes its proper position for scraping and removing the deposit. The construction is simple, economical to manufacture and particularly effective for performing the functions for which designed. In practical service it has proved its merit.

I claim:

1. A device of the class described, comprising a plate of metal, an elongated flexible wire pivotally connected to the plate at one end and adjacent one edge of the plate, said wire having a laterally extend-

ing eye formed in its length between the ends thereof, a second wire pivotally connected to the plate at one end a short distance from the pivotal connection of the first wire thereto, said second wire passing through said eye, and a stop formed at the free end of said second wire to prevent disconnection of said second wire from said eye.

2. A device of the class described comprising a plate of metal, an elongated flexible wire pivotally connected to the plate at one end and adjacent one edge of the plate, said wire having a laterally extending eye formed in its length between the ends thereof, a second wire pivotally connected to the plate at one end a short distance from the pivotal connection of the first wire thereto, said second wire passing through the eye, a stop formed at the free end of said second wire to prevent disconnection of said second wire from said eye and a coiled spring around said second wire 50 between the plate and said eye on the first wire.

In testimony whereof I affix my signature.
EDGAR W. CLEVELAND.
